UNITED STATES PATENT OFFICE

122,566

DESIGN FOR A GAME BOARD

Jorge Kirchhofer Cabral, Oslo, Norway

Application December 21, 1939, Serial No. 89,071

Term of patent 7 years

To all whom it may concern:

Be it known that I, Jorge Kirchhofer Cabral, a citizen of Brazil, residing at Oslo, Norway, have invented a new, original, and ornamental Design for a Game Board, of which the following is a specification, reference being had to the accompanying drawing, forming part thereof.

I claim:

The ornamental design for a game board, as shown.

JORGE KIRCHHOFER CABRAL.
